UNITED STATES PATENT OFFICE

2,245,030

TUBING CLAMP FOR INTRAVENOUS OPERATIONS

Benjamin Harvey Gottesfeld and Morris R. Gottesfeld, Denver, Colo.

Application July 19, 1940; Serial No. 346,340

3 Claims. (Cl. 251—5)

This invention relates to a clamping device for flexible tubing and is more particularly designed for use during intravenous operations to eliminate the danger of air embolism and to eliminate the excessive waste of intravenous fluid occasioned by present methods of eliminating air from the intravenous apparatus.

The danger of air embolism has long been recognized by the medical profession, although, due to the difficulties encountered histologically in the demonstration of air within the tissues, many cases of air embolism have gone undiscovered at post-mortem examinations. This is due to the fact that with ordinary routine fixation, fluid saturates the tissues and displaces the air within the blood vessels and end arteries (brain-kidney). Fatal cases of air embolism may be due to the air converting the blood in the heart into a froth which makes proper cardiac contraction impossible, or bubbles of air may reach the brain.

There have been no exhaustive attempts made to determine whether air embolism resulting from the inadvertent administration of air from intravenous medication has resulted in fatalities. However, it may be a contributory factor and the purpose of this improved clamp is to obviate this possibility.

It is the present practice to allow a relatively large quantity of the intravenous fluid to flow through the tubing and needle in an endeavor to wash out any air that may be contained therein. This method has been unsatisfactory, because of the fluid waste, and uncertain, since the cohesive force between the air bubbles and the rubber-tubing often prevents all of the air from being carried out by the escaping fluid. Another object of the invention is to provide an improved clamp which will positively force all of the air from the tubing without excessive waste of the fluid.

Other objects of the invention are to provide a device of this character which can be economically manufactured; which can be used by anyone without special skill or training; which will prevent damaging wear and tear on the rubber tubing; which can be quickly applied to or removed from the tubing; and which can be employed to accelerate the flow of fluid in order to cut the time element of an operation to a minimum. Time in certain operations of this class may be the determining factor between life and death of the patient.

Other objects and advantages reside in the detail construction of the invention, which is

designed for simplicity, economy, and efficiency. These will become more apparent from the following description.

In the following detailed description of the invention reference is had to the accompanying drawing which forms a part hereof. Like numerals refer to like parts in all views of the drawing and throughout the description.

In the drawing:

Fig. 1 is a perspective view illustrating the improved tube clamp in the open position on a rubber tube.

Fig. 2 is a similar view illustrating the clamp in the closed position.

Fig. 3 is a side view thereof showing the device in substantially full size.

Fig. 4 is an end view thereof.

Fig. 5 is an enlarged longitudinal section, taken on the line 5—5, Fig. 4.

Fig. 6 is an enlarged cross section, taken on the line 6—6, Fig. 3.

The invention comprises two side plates 10 provided with elongated slotted openings 11 throughout the major portion of their lengths. 25 Adjacent one extremity, each of the plates 10 is perforated to receive the extremities of a fixed roller shaft 12. The extremities of the latter are preferably reduced to form shouldered extremities 13 which extend through the perforations in the plates 10 and are riveted or otherwise secured therein to fixedly maintain the two end plates in alignment with each other. A first tubular roller 14 surrounds the fixed shaft 12 and is free to rotate thereabout.

The above described structure forms a rigid U-shaped frame carrying a roller between the two side plates. A movable roller shaft 15 extends between the side plates and is slidably mounted in the slotted openings 11. The roller shaft 15 is formed with a head 16 on one extremity. The other extremity is threaded to receive a wing nut 17. The shaft 15 is surrounded, between the plates 10, with a tubular spacing sleeve 18 upon which a second tubular roller 19 is rotatably mounted.

It can be readily seen that when the nut 17 is tightened, it will act to draw the two side plates against the extremities of the spacing sleeve 18 to clamp the shaft fixedly in position therebetween. The roller 19 is shorter than the spacing sleeve so that it will not be clamped by the side plates but will always be free to rotate. A washer 20 is preferably positioned beneath the nut 17. The tubing upon which the

device is to be used, shown at 21, is placed between the two rollers 14 and 19.

In use the improved clamp is first placed at the upper extremity of the tubing 21 immediately below the reservoir. The roller 19 is pressed tightly against the tubing to compress it completely closed. The nut 17 is then tightened to maintain the clamp in the contracted position. The clamp is then drawn downwardly along the tubing and acts to squeeze the air from the tubing ahead and to create a partial vacuum behind, into which the intravenous fluid is drawn. When the clamp reaches the lower extremity of the tube, the operator knows that all air has been expelled from the tubing.

It is preferred to allow a very small quantity of the fluid, say 5 cc., to pass between the rollers before the preliminary contraction to insure wetting of the internal tubing surfaces and to provide a positive seal at the contracted point. When the bottom of the tube is reached, the rollers are slightly separated to allow a small quantity of the fluid to flow through the needle to exhaust the air therefrom.

Control of the rate of flow of the fluid is obtained by widening or narrowing the distance between the two rollers. If it is desired in the particular operation being performed to speed up the flow of the fluid over the natural gravitational flow, the rollers may be separated and the clamp again lifted to the top of the tube. The rollers are then again brought together and drawn downwardly along the tubing to create a pressure in the fluid proceeding them. This process can be repeated until the indicated amount of fluid has been transferred.

It will be noted that only the rounded roller surfaces contact the tube so that there is no cutting or abrading action thereon.

It is believed that the advantages of the improved clamp are apparent from the above description. Briefly, it obviates any possibility of air embolism; it saves from 80 to 100 cc. of expensive intravenous fluid from each liter; it can be used to speed up the administration of fluids; and it prevents cutting or the damaging of the rubber tubing.

Investigation has shown that approximately 30,000 cc. of intravenous fluid is used daily in the average 150 bed surgical hospital for intravenous medication. Of this amount 3,000 cc. goes to waste in flushing rubber tubing. In one year, therefore, 1,095,000 cc. are wasted. At the prevailing market this is a total loss of approximately \$1,200. In order to compensate for this loss of fluid, most of the fluid supply companies build their solution bottles to contain 1100 to 1200 cc. This necessitates larger sized bottles and adds to the cost of transportation. With this improved clamp, however, this loss, the increased size of bottles, and excess transportation cost will be avoided.

While a specific form of the improvement has been described and illustrated herein, it is desired to be understood that the same may be

varied, within the scope of the appended claims, without departing from the spirit of the invention.

Having thus described the invention, what is claimed and desired secured by Letters Patent is:

1. A clamping device for rubber tubing comprising: two elongated side plates; a fixed shaft extending between the said side plates and fixed to one extremity of each; a roller rotatably mounted on said fixed shaft; a movable shaft extending between said side plates through slotted openings therein; a nut threaded on one extremity of said latter shaft; a head formed on the other extremity thereof so that when said nut is rotated, said two side plates will be urged together; a second roller mounted on said latter shaft; and means for preventing the side plates from being drawn into contact with the said second roller.

2. A clamping device for rubber tubing comprising: two elongated side plates; a fixed shaft extending between the said side plates at their one extremity; a roller rotatably mounted on said fixed shaft; a movable shaft extending between said side plates through slotted openings therein; a nut threaded on one extremity of said latter shaft; a head formed on the other extremity thereof so that when said nut is rotated, said two side plates will be urged together; a second roller mounted on said latter shaft; a tubular spacing sleeve surrounding said movable shaft between said side plates, said sleeve serving as a bearing for said second roller and also acting to prevent the plates from being drawn against the extremities of the second roller.

3. A rolling clamp for rubber tubing of the type adapted to be contracted against and moved longitudinally of a rubber tubing to force fluid therefrom comprising: two similar, elongated side plates each provided with an elongated slotted opening extending the major portion of its length and with a perforation adjacent its one extremity; a separating shaft; shouldered extremities on said separating shaft, each extending into one of said perforations and being secured therein to hold said side plates in fixed parallel relation with each other; a first tubular roller surrounding the separating shaft and being free to rotate thereon; a movable roller shaft extending between the side plates and through the slotted openings therein; a head on one extremity of said movable roller shaft; a wing nut threaded on the other extremity thereof; a tubular spacing sleeve surrounding said movable roller shaft between said side plates so that when said nut is tightened the plates will be clamped against the ends of the spacing sleeve to lock the movable shaft in said slotted openings; and a second tubular roller surrounding said spacing sleeve, said latter roller being of less length than said spacing sleeve so that it cannot be clamped between said side plates.
